UNITED STATES PATENT OFFICE.

ALVAR LENNING, OF NEWBURGH, NEW YORK, ASSIGNOR TO ELECTROLUX SERVEL CORPORATION, OF NEW YORK, N. Y., A CORPORATION OF DELAWARE.

REFRIGERATION.

Application filed September 9, 1927. Serial No. 218,418.

My invention relates to refrigeration and more particularly to the construction of evaporators or chilling units for refrigeration systems or machines. One purpose of the invention is to provide an evaporator which has large heat transmission area, is compact, neat, efficient and durable while easily assembled and the parts of which are securely combined. Another object is to provide a novel ice freezing and dessert chilling arrangement, the advantages of which will become apparent as the description proceeds. The invention is included in the structure shown by way of example on the accompanying drawings, of which: Fig. 1 is an elevational view, partly broken away and partly in cross-section showing an evaporator built and assembled according to the invention and situated within a refrigerator cabinet; Fig. 2 is a top view, partly in cross-section, taken on line 2-2 of Fig. 1; and Fig. 3 is a top view, partially in cross-section, of a somewhat modified form of evaporator casting.

Reference character 10 designates the evaporator generally. The term evaporator is here used as a general term for the combined arrangement of a receptacle in which evaporation or boiling takes place and a surrounding structure for transmitting heat, the ensemble being otherwise known as a chilling unit. The evaporator is situated within a refrigerator cabinet 9, suitably insulated. The evaporator shown is particularly adaptable for use as part of an absorption type refrigerating apparatus such as shown and described in Patent No. 1,609,334, granted December 7, 1926, though it is not limited to such apparatus.

The evaporator comprises a shell 12 of cylindrical form with rounded ends and a surrounding casting 8, which latter is preferably, though not necessarily, constructed of aluminum. Shell 12 is arranged with its axis extending vertically and is connected to and supported on a heat exchanger 32 which extends horizontally through and is supported by the cabinet wall and is suitably connected to remaining parts of the refrigerating apparatus. Shell 12 is made of steel to withstand high internal pressure. It is supplied with liquid refrigerant, such as ammonia, through conduit 13 and with a gas, inert with respect to the refrigerant, such as hydrogen, through conduit 14. Conduit 13 passes with-

in conduit 14 and within heat exchanger 32. 55 Conduit 33 connects the bottom of shell 12 with one space of heat exchanger 32 and conduit 14 is connected to a space of the heat exchanger separated from the space to which conduit 33 is connected. The shell 12 is provided internally with a vertically disposed series of horizontal disks 15 provided with apertures 16 and 34 for flow of gas and liquid respectively.

Heat transmitting member 8, preferably a 65 casting, comprises a box-like compartment 20 formed by vertically extending straight side walls 36, a vertically extending back wall 37, and plane top and bottom walls 38 and 39. This compartment is open to the front 70 of the cabinet and has transversely extending shelves 21 dividing the compartment into a plurality of relatively narrow spaces 41, each substantially filled by one of a series of given size ice trays and a larger space 42 at 75 the top large enough to accommodate two of the given size ice trays, one above the other. The ice trays are indicated by dotted lines 44. Space 42 has in it a pair of ledges 24 attached to side walls 36. These ledges extend horizontally and serve as hangers for an ice tray, the ice trays having outwardly bent edges for this purpose, as indicated. Space 42 is sufficiently large so that when one of the ice trays is suspended from ledges 24, another 80 ice tray may be placed under it on the shelf 21 forming the bottom of space 42. Shelves 21 are provided with drain holes 31 and ridges 22 on which the ice trays slide. The front of compartment 20 may be closed by 85 a cover member (not shown) which is supported by top wall 38.

Extending laterally from the box-like compartment 20 are two arcuate arms 46 and 47 of partial cylinder form and integral with the 95 casting. These bent arms encircle shell 12 and approach but do not touch each other on the side of the shell opposite the box-like compartment 20. To the outer ends of arms 46 and 47 are affixed flanges 17. The flanges may extend the entire height of the arms 46 and 47 or to a point below the upper horizontal part of conduit 14, as shown. A plurality of holes are formed in flanges 17 through which bolts 18 are passed, which, when tightened by nuts, serve to draw the flanges toward each other and to securely clamp the heat transmitting casting 8 around the shell 12. 100

The arrangement is such that when bolts 18 are drawn up tight, there is still space 56 between the flanges so that there is an internal stress in the metal of the arms 46 and 47.

18 The inside of arms 46 and 47 are provided with vertical grooves 19. These grooves increase the flexibility of the clamping arms and serve as drain passages for condensate.

19 A front vertical wall 26 is cast integral with box-like compartment 20. Wall 26 serves to improve the appearance of the evaporator by concealing arcuate arms 46 and 47 and bolts 18. It also increases the heat transfer surface of the casting. The surface is further increased and the casting strengthened by a side vertical wall 25 cast integral with front wall 26 and arm 47. A web member 27 also extends between wall 26 and arm 47 and forms, in part, vertically extending passageways 28 and 29 through which air may circulate. The surface of the casting is still further increased by vertically extending fins 30 on walls 26 and 25, arm 46 and one side of box-like compartment 20.

20 25 The evaporator assembly 10 is supported partially by heat exchanger 32 and partially by a plurality of brackets 45.

20 30 The low temperature maintained within evaporation chamber 12 by reason of the evaporation of the refrigerant therein causes heat to flow thereto from casting 8. The casting is thereby maintained at a low temperature and in turn absorbs heat from the water placed in ice freezing trays 44 and from the surrounding air.

30 45 The evaporator casting shown in Fig. 3 is a modified form of the casting shown in Figs. 1 and 2. Reference character 8 designates, as before, the casting generally which comprises box-like compartment 20 and arcuate arms 46 and 47. A plurality of shelves 50 are provided in compartment 20, having a space-relation similar to shelves 21 in Fig. 1, for the reception of ice trays. However, shelves 50 differ from shelves 21 in that the former extend more or less around three sides of compartment 20 rather than all the way across the compartment. Because of this formation of shelves 50, ridges and drain holes are not required except in the bottom wall 39 of the compartment which is provided with two parallel ridges 22 and two drain holes 31.

45 55 Arcuate arms 46 and 47 are cast integral with compartment 20. Arm 46 has a plurality of holes 51 formed therethrough near its outer end while arm 47 has corresponding holes 52 threaded and extending only part way through the arm. Bolts (not shown) pass through holes 51 and screw into holes 52 and serve to draw arms 46 and 47 toward each other in order to clamp the casting to a cylindrical evaporation chamber, as is designated at 12 in Fig. 2.

55 65 A plurality of fins 30 are cast integral with arms 46 and 47 and the front of compartment

20 65 Fins 30 serve to increase the surface of casting 8 and thus increase the rate of heat transfer between the surrounding air and the chilling unit. A number of vertically extending grooves 19 are formed in the inner faces 70 of arms 46 and 47 for the reason explained in connection with Figs. 1 and 2.

70 While I have shown specific embodiments of my invention, it is to be understood that variations in structural design fall within its 75 scope. For instance, box-like compartment 20 may be designed with two large spaces and one small one, both large spaces being provided with a pair of ledges similar to ledges 24 (Fig. 1) or the compartment may be made 80 large enough to comprise three large spaces or any combination of large and small spaces that is desired.

80 Having described my invention, what I claim is:

85 1. A refrigerator comprising a cabinet, an evaporator within said cabinet, said evaporator comprising a shell, a heat transmitting casting comprising a box-shaped portion adapted to hold ice trays, a plurality of arms 90 extending from said box-shaped portion and encircling said shell, and tightening means for drawing said arms toward each other.

90 95 2. A refrigerator comprising a cabinet, an evaporator within said cabinet, said evaporator comprising a shell, a heat transmitting casting comprising a box-shaped portion adapted to hold ice trays, a pair of arcuate members extending laterally from said box-shaped member and encircling said shell, and means for drawing the pair of arcuate members toward each other to stress them against the shell.

100 105 3. A refrigerator comprising a cabinet, an evaporator within said cabinet, said evaporator comprising a cylindrical shell having a vertical axis and supported by said cabinet, a heat transmitting member comprising a box-shaped portion having walls forming a compartment adapted to hold ice trays, a set 110 of bent arms extending laterally from said box-shaped portion and encircling said shell, flanges at the outer ends of said arms, and means to draw said flanges toward each other.

110 115 4. A refrigerator comprising a cabinet, an evaporator within said cabinet, said evaporator comprising a cylindrical shell having a vertical axis and supported by said cabinet, a heat transmitting member comprising a box-shaped portion having walls forming a compartment adapted to hold ice-trays, a set 120 of bent arms extending laterally from said box-shaped portion and encircling said shell, flanges at the outer ends of said arms, holes in said flanges and bolts extending through said holes for drawing said flanges toward each other, the arrangement being such that the flanges are separated when the bolts are drawn up tight.

120 125 5. An evaporator comprising a shell a heat

- transmitting member comprising a box-shaped portion having walls forming a compartment for ice trays, a set of bent members extending laterally from said box-shaped portion and encircling said shell, flanges at the outer ends of said bent members and tightening members extending through said flanges for drawing said bent members toward each other.
- 10 6. A refrigerator comprising a cabinet, an evaporator within said cabinet, said evaporator comprising a steel shell, a heat transmitting member of relatively light material comprising a box-shaped portion having walls forming a compartment adapted to hold ice trays, a set of bent arms extending laterally from said box-shaped portion and
- 15 encircling said shell, flanges at the outer ends of said arms and means to draw said flanges together.
7. A refrigerator comprising a cabinet, an evaporator within said cabinet, said evaporator comprising a steel shell, a heat transmitting member of relatively light material comprising a box-shaped portion having walls forming a compartment adapted to hold ice trays, a set of bent arms extending laterally from said box-shaped portion and encircling said shell, flanges at the outer ends of said arms and means to draw said flanges together. 30

In testimony whereof I hereunto affix my signature.

ALVAR LENNING.
